DESIGN FOR A COMBINED HAND AND UTILITY BAG

Rudolph Lobel, New York, N. Y.

Application June 19, 1940, Serial No. 93,089

Term of patent 3½ years

To all whom it may concern:

Be it known that I, Rudolph Lobel, a citizen of the United States and resident of New York city, in the county of New York and State of New York, have invented a new, original, and ornamental Design for a Combined Hand and Utility Bag, of which the following is a specification, reference being had to the accompanying drawing, forming a part thereof, and of which Figure 1 is a view in front elevation closed position of a combined hand and utility bag showing my new design; Fig. 2 is a view thereof in end elevation;

Fig. 3 is a view thereof in front elevation, but with the bottom tab open; Fig. 4 is an inside plan view of the device open to show the utility bag; Figs. 5 and 6 are sectional views thereof on the lines 5—5 and 6—6 respectively of Fig. 4.

The back of the article illustrated, not shown, is substantially plain.

I claim:

The ornamental design for a combined hand and utility bag, substantially as shown and described.

RUDOLPH LOBEL.
